The ornamental design for a medical clothing for pet as shown and described.

DESCRIPTION

FIG. 1 is a top view of a medical clothing for pet, shown in a first configuration with the rear panel opened;

FIG. 2 is a bottom plan view;

FIG. 3 is a right-side elevation view of the medical clothing for pet, shown in a second configuration with the rear panel closed;

FIG. 4 is a left-side elevation view thereof;

FIG. 5 is a rear elevation view thereof;

FIG. 6 is a front elevation view thereof; and,

FIG. 7 is a top perspective view thereof.

In the drawings, the equal-length broken lines depict portions of the medical clothing for pet that form no part of the claimed design.

The drawings are shaded to indicate contrasting surfaces.
